H. A. FEIGELMAN

SPOOL

Filed Feb. 23, 1924

WITNESS

W. Shell

INVENTOR,
Herman A. Feigelman,

John Edward
ATTORNEY

UNITED STATES PATENT OFFICE.

HERMAN A. FEIGELMAN, OF PATERSON, NEW JERSEY.

SPOOL.

Application filed February 23, 1924. Serial No. 694,555.

To all whom it may concern:

Be it known that I, HERMAN A. FEIGELMAN, a citizen of the United States, residing at Paterson, in the county of Passaic and State of New Jersey, have invented certain new and useful Improvements in Spools, of which the following is a specification.

This invention relates to spools or the like on which to wind ribbon and the like and when so used usually known as "ribbon blocks." One object of the invention is to provide a device of this kind which can be cheaply manufactured and which shall be strong and durable. Another object is to provide for its adjustability lengthwise of its barrel, or between the heads or flanges of the device.

In the drawing,

Fig. 1 is an end elevation of the improved spool;

Fig. 2 is a side elevation, partly in section;

Fig. 3 is a side elevation of one end of the spool, partly broken away; and

Figs. 4 and 5 are isometric views of the sections of the barrel when the spool is constructed to be longitudinally adjustable.

The barrel is designated *a* and the two heads or flanges *b*.

In the example shown the barrel includes tubular or other hollow barrel sections *a'* *a''* which are telescoped one into the other, the one fitting the other snugly. These sections may be formed of any suitable sheet material, but in furtherance of certain other features of the invention which will appear it is preferable that the barrel be composed of sheet metal. In the best form, one of the sections, as the inner one *a''*, is split lengthwise, as shown, for its full length. One section, as the section *a''*, has a succession of notches *c* (as shown, being actual holes through the material) arranged in a lengthwise extending series, in the example illustrated being all in the same plane as the axis of the section. Another such series of notches may be formed diametrically opposite the first series, as shown at *c'*. The other section *a'* has at its inner end a spur or projection *d* to engage in one of the notches of the series *c*, and it may also have opposite this projection a projection *d'* to engage the series of notches *c'*, if present.

To engage the tangs or projections each in one of the notches of the two series the sec-

tion *a''* is constricted (possible because in the illustrated example it is split at *a''*) and then moved longitudinally of the other section to effect such engagement. It will be understood that adjustment of the spool longitudinally is very desirable so as to adapt it for different widths of ribbon or in general to alter its capacity.

The ends of the barrel are provided with tongue-extensions *e*, each of which is bent inward and lies in a plane intersecting the axis of the barrel—here a plane as to which the axis is perpendicular. Before assembling the barrel with either head *b* the end of each tongue-extension is bent outward, and where, as usual, there are several of these tongue-extensions at the end of the barrel, they will be arranged in equally spaced radii so that their outwardly bent ends *e'* will be grouped around the axis of the barrel. Each head is composed of sheet material, as paste-board. The extremity *e'* of each tongue-extension is rebent and clinched upon the material of the head in attaching the latter to the barrel, as by first introducing such extremity through a hole *f* in the head and then causing the rebending and clinching to be effected at and on the edge of the hole, as shown in Figs. 1 to 3.

It may be sufficient in many cases to fasten each head to the barrel substantially as I have described, using only the tongue-extensions. But to prevent any possibility of slippage or looseness of either head with respect to the barrel, and also to augment the union between each head and the barrel, I may provide the end of the barrel with tangs *g* which can be driven into the head and if desired then upset, as shown in Fig. 3.

It will be observed that the bent-over inner ends of the tongue-extensions form durable bearings for the spool. This is important where the heads or flanges *b* are composed of paste-board material, which would soon wear away if the bearing holes therein were not thus protected.

Having thus fully described my invention, what I claim as new and desire to secure by Letters Patent is:

1. A spool including a metallic hollow barrel having a tongue-extension at one end thereof bent inward and lying in a plane intersecting the axis of the barrel, and a head bearing against the end of the barrel, said tongue-extension having its ex-

- tremity rebent and clinched upon the material of the head.
2. A spool including a metallic hollow barrel having a tongue-extension at one end thereof bent inward and lying in a plane intersecting the axis of the barrel, and a head bearing against the end of the barrel and having an aperture substantially central of the barrel, said tongue extension having its extremity rebent and clinched upon the edge of the hole in the head.
3. A spool including a metallic hollow barrel having a tongue-extension at one end thereof bent inward and lying in a plane intersecting the axis of the barrel, and a head bearing against the end of the barrel, said tongue-extension having its extremity rebent and clinched upon the material of the head and the barrel also having at said end tangs engaged in the material of the head and coacting with the tongue-extension to secure the head immovably to the barrel.
4. A spool including a hollow barrel, said barrel comprising sections both of sheet material telescoped one into and snugly fitting the other, and a head secured to the relatively outer end of each section, one section having a longitudinal succession of notches and the other an integral projection to engage in one or the other of the notches.
5. A spool including a hollow barrel, said barrel comprising sections both of sheet material telescoped one into and snugly fitting the other, and a head secured to the relatively outer end of each section, one section being split lengthwise and one section having a longitudinal succession of notches and the other an integral projection to engage in one or the other of the notches.

In testimony whereof I affix my signature.
HERMAN A. FEIGELMAN.
